UNITED STATES PATENT OFFICE

OLIVER F. CAMPBELL, OF WHITING, INDIANA, AND EUGENE C. HERTEL, OF CHICAGO, ILLINOIS, ASSIGNORS TO SINCLAIR REFINING COMPANY, OF NEW YORK, N. Y., A CORPORATION OF MAINE

ART OF COKING HEAVY OILS

Application filed March 7, 1929. Serial No. 344,952.

This invention relates to improvements in the coking of heavy oils, such as crudes, topped crudes, flux oils, other residual oils and the like. More particularly, this invention relates to improvements in such coking operations in which a charge of coke is formed and deposited within a coking receptacle from which this coke product must be discharged. Commercially, lump coke is more valuable than coke fines. The improvements of this invention assist particularly in increasing the production of lump coke and in decreasing the production of coke fines in such coking operations. Other advantages of the invention will be apparent as the description proceeds.

The invention is particularly useful in connection with the operations described in applications Serial No. 340,996, filed February 18, 1929, Patent No. 1,831,719 dated November 10, 1931, and Serial No. 341,214 filed February 19, 1929, by Harry L. Pelzer and Serial No. 347,533 filed March 16, 1929, by Edward W. Isom and George H. Taber, jr., but, as will be apparent, it is of more general application.

Most of the fines produced in such coking operations are produced, not during the coking operation proper, but during the discharge of the coke product from the coking receptacle, and such fines are produced by the disintegration of what otherwise would be lump coke. This discharge of the coke product has been effected, heretofore, in a number of ways ranging from the crude digging out of the coke product to more refined methods involving the prearrangement of chains or cables within the coking receptacle so that, at the termination of the coking operation proper, the chains or cables extend through the body of the coke charge so that the coke product can be broken up within the receptacle and discharged by pulling out the chains or cables.

This invention provides for the removal of the bulk of the coke product from the coking receptacle as large coherent blocks which can be broken up for sizing as desired with a minimum production of coke fines and a maximum production of lump coke. The

discharge of the coke product from the coking receptacle is, moreover, through this invention, much simplified and much expedited, making it possible to keep the coking receptacle in use for carrying out the coking operation proper a greater proportion of the time. 55

According to this invention, a radially thin annulus of the charge of coke in the coking receptacle, a cylindrical coking receptacle being used, is removed immediately adjacent the wall of the coking receptacle at the termination of the coking operation proper and the remaining bulk of the coke charge is then removed as a single block or as a relatively small number of large blocks. 60 65

In carrying out this invention, in a particularly advantageous manner, a cable is pre-arranged within the coking receptacle in closely wound turns, touching or nearly touching, lying just within the wall of the coking receptacle and, at the termination of the coking operation proper, this cable is pulled out leaving an annular space somewhat thicker, radially, than the diameter of the cable immediately adjacent the wall of the coking receptacle and leaving the bulk of the coke as a free block or blocks within the coking receptacle, and this block coke is then discharged en bloc through one or the other of the heads of the coking receptacle. By 70 75 winding the turns of the cable as closely as possible, as prearranged within the coking receptacle, a minimum of the coke charge is broken up when the cable is pulled out, and the stress on the cable is also thus reduced. 80 85

In carrying out this invention, in its broader aspects, the radially thin annulus of the charge of coke may be removed immediately adjacent the wall of the coking receptacle as just described or, as a further example, as described in application Serial No. 345,016, filed March 7, 1929, by William S. Gullette.

This invention will be further described in 95 connection with the accompanying drawing which illustrates, diagrammatically and conventionally, one form of apparatus adapted for the practice of the invention, but it is intended and will be understood that this 100

more detailed description and illustration are simply by way of exemplification.

In the accompanying drawing, Fig. 1 represents in elevation a coking receptacle, Fig.

5 2 represents a frame carrying a cable lining for the coking receptacle, and Fig. 3 is an end view of the frame illustrated in Fig. 2.

Referring to the drawing, the heavy oil stock to be reduced to coke is sprayed into

10 the upper end of the coking receptacle 4 through connection 5, the hot vapors from a vapor phase cracking operation, for example, are released within the lower end of the coking receptacle 4 through connection 6, and

15 the vapor mixture resulting from the coking operation is discharged from the upper end of the coking receptacle 4 through connection 7. The coking operation proper may be carried out, for example, as described in any of

20 the applications Serial Nos. 340,996, 341,214 or 347,533, mentioned above. The coking receptacle 4 may, for example, be a drum 9' in diameter and 30' high. The cable lining for the coking receptacle 4 is wound upon a

25 frame comprising a plurality of rods or bars 8 supported by one or more spiders 9. For use in a coking receptacle of the dimensions just given, the spiders 9 may be dimensioned to hold the rods or bars 8 on a circle, for ex-

30 ample, 8' 6" in diameter. The cable may consist, for example, of a 1" steel wire rope. When positioned within the coking receptacle 4, the cable lining frame, comprising the spiders 9 and the rods or bars 8, is sup-

35 ported by means of cable 10 extending through a gland in the upper head 11 of the coking receptacle and carried, for example, by an I-beam 12 arranged above the coking receptacle, the lower head 13 is of the full

40 diameter of the coking receptacle 4. This large-diameter head may be sealed, for example, as described in application Serial No. 344,940, filed March 7, 1929, Patent No. 1,819,095 dated August 18, 1931, by Eugene

45 C. Herthel.

In carrying out the invention with the apparatus illustrated, assuming the coking receptacle 4 clean and open, a cable is closely wound, as shown in Fig. 2, on the cable lining

50 frame. This frame carrying the cable lining is then placed in the coking receptacle 4 and secured to the supporting cable 10. The lower head 13 is then clamped in place and the coking operation carried out. At the termina-

55 tion of the coking operation proper, the lower head 13 is removed. The cable forming the cable lining wound on the cable lining frame is then pulled out through the lower end of the coking receptacle 4 by means of a winch.

60 This removal of the cable lining leaves an annular space somewhat thicker, radially, than the diameter of the cable immediately adjacent the wall of the coking receptacle and leaves the bulk of the coke as a free block or

65 blocks within the cable lining frame and sup-

ported within the coking receptacle 4 by means of the cable 10. The cable lining frame and the remaining coke charge are then lowered out of the coking receptacle 4 by means of the supporting cable 10. Another cable lining frame carrying a cable lining, usually prepared during the preceding operation, is then placed within the coking receptacle 4 and the operation resumed, as described. A small amount of coke may remain adhering to the wall of the coking receptacle 4, after removal of the cable lining, but this may be disregarded so long as this coke accumulation does not interfere with the insertion of the next cable lining.

In a coking receptacle 9' in diameter and 30' high, the coke product may be discharged, for example, as a single block 8' 6" in diameter and 20' or more long.

We claim:

1. In coking heavy oils in a cylindrical coking receptacle, the improvement which comprises reducing a charge of heavy oil to coke in the receptacle and, at the termination of the coking operation proper removing a radially thin annulus of the body of coke immediately adjacent the wall of the coking receptacle, and then removing the remaining bulk of the coke body en bloc.

2. In coking heavy oils in a coking receptacle in which a cable is prearranged within the coking receptacle in closely wound turns lying just within the wall of the coking receptacle, the improvement which comprises reducing a charge of heavy oil to coke in said receptacle and, at the termination of the coking operation proper pulling the cable out of the coking receptacle, and then removing the remaining bulk of the coke body en bloc.

In testimony whereof we affix our signatures.

OLIVER F. CAMPBELL.
EUGENE C. HERTHEL.
